UNITED STATES PATENT OFFICE.

DESIGN FOR A BAG.

SPECIFICATION forming part of Design No. 19,161, dated June 18, 1889.

Application filed May 9, 1889. Serial No. 310,146. Term of patent 14 years.

To all whom it may concern:

Be it known that I, SOLOMON HENRY HOWE, of the city, county, and State of New York, have invented and produced a new and original Design for Bags, of which the following is a full, clear, and exact specification, reference being had to the accompanying drawings, forming part thereof.

Figure 1 is a face view of my newly-designed bag for confectionery, toys, and the like, and Fig. 2 is a similar view of the reverse side of the bag.

The design comprises in one of its features a bag having the general shape of a stocking, the handle or loop of said stocking-shaped bag representing a strap with a buckle securing its ends. On one side of the stocking-like bag its ornamentation comprises a pictorial representation of a fire-place produced on the leg of the stocking-like bag, at the side of which appear the fire-tongs and fire-shovel, a clock and candlesticks being represented on the mantel, and stockings being represented as hanging from said mantel; also, below the pictorial representation of the fire-place, at about the ankle portion of the stocking-like bag, appears the pictorial representation of a child in bed, at the side of the bedstead appearing the representation of a chair.

The design of the reverse side of the stocking-like bag comprises near the top the pictorial representation of a house, the house and surrounding ground being represented as snow-covered, and on the roof of the house appears the pictorial representation of St. Nicholas, or Santa Claus, carrying on his back a miscellaneous assemblage of toys. Below the representation of the house and St. Nicholas are represented reindeer harnessed to a sleigh, the sleigh being represented as on a low log 40 bridge. The whole ornamentation of my newly-designed bag thus represents scenes associated with the mythical visits of St. Nicholas, the scenes being arranged to produce a design attractive to children. 45

Referring to the drawings, A indicates one side of the stocking-like bag, B the reverse side, and C the handle. D indicates the representation of the fire-place and appurtenances; E, the bedstead and accompanying 50 representations; F, the snow-covered house with the accompanying representation of St. Nicholas; G, the reindeer and sleigh, and H the representation of a log bridge.

The several features of the ornamental decorations of each side of the stocking-like bag appear in vertical arrangement. 55

I claim—

1. The design for a bag, substantially as shown in the accompanying drawings. 60
2. The design for a bag herein shown and described, the same having the general form of a stocking, on one side of which appear the representation of a fire-place and mantel with stockings hanging from the mantel and the representation of a child in bed. 65
3. The design for a bag herein shown and described, the same having the general form of a stocking, on one side of which appear the representation of a snow-covered house, a representation of St. Nicholas with toys on the roof, and reindeer harnessed to a sleigh appearing below the representation of the house. 70
